STARTING BLOCK

Everett F. Niday, Altadena, Calif.

Application January 15, 1934, Serial No. 706,686

7 Claims. (Cl. 272—59)

This invention relates to starting blocks.

The general object of the invention is to provide an improved starting block for the use of runners.

A more specific object of the invention is to provide a runner's starting block which is constructed of metal and wherein the parts can be assembled, adjusted and disassembled without the use of implements of any kind.

A further object is to provide a starting block including a foot plate wherein novel means is provided for positively holding the foot plate in the desired angular position.

Another object is to provide a starting block including a body, a foot plate and a brace which folds to a flat position when collapsed.

Other objects of my invention will be apparent from the following description taken in connection with the accompanying drawing wherein:

Fig. 1 is a top plan view of a starting block embodying the features of my invention;

Fig. 2 is a section taken on line 2—2 of Fig. 1;

Fig. 3 is a view similar to Fig. 2 showing the parts in another position;

Fig. 4 is a section taken on line 4—4 of Fig. 1;

Fig. 5 is a section taken on line 5—5 of Fig. 2; and,

Fig. 6 is a sectional detail showing a modification.

Referring to the drawing by reference characters I have indicated my starting block generally at 10. As shown the starting block comprises a body indicated generally at 11, a toe plate indicated at 12 and a brace member indicated generally at 13.

The body 11 includes a pair of side members 14 which are held in parallel spaced apart relation by end members 15. At the junction of the sides and ends I provide downwardly projecting spike members 16 which are adapted to be pushed into the ground to hold the starting block against movement.

The opposed inner faces of the side members 14 are provided with inwardly directed longitudinally extending grooves 17. Adjacent the front of the sides, the grooves 17 intersect downwardly directed grooves 18 which extend to the bottom of the sides. At the rear of the grooves 18 I provide pairs of aligned grooves 19 which are arranged in spaced relation. These grooves 19 terminate short of the bottom of the sides so that their lower ends are closed. A pair of aligned inwardly directed bosses 20 are arranged at the rear of the grooves 19. At the rear end the sides 14 are provided with opposed slots 21 which have enlarged inner portions 22.

The brace member 13 comprises a pair of spaced side members 23 and a pair of end members 24 and 25. The end member 25 is provided with trunnions 26 which fit in the grooves 21. The trunnions 26 have parallel sides so that when the brace is held in the position shown in Fig. 4 the trunnions may be moved to the bottoms of the respective slots, thus allowing pivotal movement of the brace member 13. The end member 24 includes a pair of end trunnions 27 which fit in slots 28 which are arranged in lugs 29 in the toe plate 12.

The toe plate 12 comprises an arcuate body portion 30 the upper surface of which may be suitably roughened. The toe plate also includes an apron 31 which is integral with the body. Ribs 32 connect the ends of the apron with the body 30. The length of the apron 31 may be varied and the angular relation of the apron 31 to the body 30 may be varied to suit the requirements of the user.

The starting blocks are used in pairs and most runners prefer one angular relation between the apron 31 and the body 30 for one foot and a different angular relation between the apron 31 and the body 30 for the other foot.

In order that the inclination of the body 30 may be varied relative to the horizontal, the body 30 is provided with a trunnion 33 at each side thereof and near the apron 31. These trunnions 33 slide in the grooves 17 and may be positioned when in use by a runner in either the front or the rear pair of grooves 19. In collapsed position the trunnions 33 are moved forwardly so that they pass downwardly through the slots 18 to the dotted line position shown in Fig. 2, where the apron 31 engages the front cross member 15 to prevent further downward movement of the toe plate 12.

When the parts are collapsed so that the apron 31 engages the front cross member 15 the side members 23 of the brace 13 engage the top of the bosses 20 to prevent further downward movement of the brace 23.

To disassemble the device the trunnions 23 are moved rearwardly to the position shown in Fig. 3. The end trunnions 27 can be moved out of the slots 28 thus freeing the brace from the toe plate. The brace is then moved to the position shown in Fig. 4 where its trunnions 26 can be moved from the slots 21 to separate the brace member from the body 10. The toe plate may then be moved forward until the trunnions 33 thereon pass downwardly through the grooves 18 to free the toe plate from the body.

In assembling the device a reversible operation to that just described is performed.

In Fig. 6 I show a modification of the invention wherein the side member 14' has a cross member 15' thereon which is provided with a threaded recess in which a short spike 35 may be removably inserted. The spikes 35 are employed when the starting device is used for indoor running. The upper surface of the sides 14 preferably have a scale 36 thereon to aid in placing the starting blocks.

10 In Fig. 7 I show a modification wherein the trunnions 37 are located beneath the forward end of the apron 38 of the toe plate 39. I have found this arrangement preferable in some instances.

15 From the foregoing it will be apparent that I have invented a novel form of starting block which is highly efficient in use and which can be economically manufactured.

Having thus described my invention, I claim:

20 1. In a starting block, a body, a foot plate having one end slidably mounted on said body and means on the body to support the other end of the foot plate.

25 2. In a starting block, a body comprising a rectangular frame, a brace pivoted to said body, a foot plate slidably mounted on said body and means to pivotally connect one end of the foot plate to the brace.

30 3. In a starting block, a body comprising a rectangular frame having means thereon adapted to be embedded in a running surface, a brace pivoted at one end to said body, a foot plate, means to slidably mount one end of the foot plate on said body and means to pivot the other end of the foot plate to the other end of the brace.

35 4. In a starting block, a body having sides, said sides having opposed grooves therein, a foot plate including a body adapted to be engaged by the sole of the shoe of the user, said plate having laterally projecting trunnions thereon at one end fitting slidably in said grooves, said grooves having aligned spaced closed slots communicating therewith, said trunnions being adapted to be adjustably mounted in said slots, and means to support the other end of said foot plate.

5. In a starting block, a body having sides, said sides having opposed grooves therein, a brace pivotally mounted at one end of said body, a foot plate, said foot plate at one end having trunnions thereon fitting said grooves, said brace at the other end having pivot means thereon engaging the foot plate, said foot plate including a body adapted to be engaged by the sole of the shoe of the user, said foot plate having laterally projecting trunnions thereon fitting slidably in said grooves, said groove having spaced closed slots communicating therewith, said trunnions being adapted to be adjustably mounted in said slots.

6. In a starting block, a rectangular body having parallel sides, said sides having opposed grooves therein, a brace pivotally mounted at one end of said body, a foot plate, said foot plate at one end having trunnions thereon fitting said grooves, said brace at the other end having pivot means thereon engaging the foot plate, said foot plate including a body adapted to be engaged by the sole of the shoe of the user and having an apron at the lower end adapted to be engaged by the toe of the user, said grooves having aligned spaced closed slots communicating therewith, said trunnions being adapted to be adjustably mounted in said slots and said sides having other slots and having inwardly directed lugs thereon.

7. In a starting block, a body having means thereon adapted to engage the surface of a running track, said body including longitudinally extending spaced side members and end members, a foot plate, said foot plate having trunnions projecting from the opposite sides thereof, one end of said foot plate being fitted between said side members, said side members including apertures in which said trunnions are fitted, a brace, said brace including one end portion fitted between said side members and pivoted to the side members, and means on the other end of the brace member releasably engaging the other end of the foot plate to hold the foot plate in elevated position.
